United States Patent Office.

HARVY GRAY, OF BRISTOL, CONNECTICUT, ASSIGNOR TO ALBERT J. SESSIONS, OF SAME PLACE.

Letters Patent No. 67,645, dated August 13, 1867.

IMPROVEMENT IN THE MANUFACTURE OF TRUNK-ROLLERS.

The Schedule referred to in these Letters Patent and making part of the same.

TO ALL WHOM IT MAY CONCERN:

Be it known that I, HARVY GRAY, of Bristol, in the county of Hartford, State of Connecticut, have invented a new and improved Mode of Making Trunk-Rollers; and I do hereby declare that the following is a full, clear, and exact description thereof, which will enable others skilled in the art to make and use the same, reference being had to the accompanying drawings, making a part of this specification, in which—

Figure 1 is a perspective view of my invention.

Figure 2 is a view of the roller and pivot.

Figure 3 is a view of the pattern for the frame.

Figure 4 is a view of an ordinary trunk-roller.

My invention consists, first, of casting the frame of a trunk-roller around the ends of the pivot or wire on which the roller revolves; second, of making a small slot or groove on each side of the pattern of the frame, and placing the ends of the pivot or wire in the slots or grooves preparatory to moulding.

a designates the roller, and *c* designates the pivot or wire on which it revolves. After placing the roller *a* on the pivot or wire *c*, as shown in fig. 2, the ends of the wire or pivot *c* are placed in the slots or grooves *d d* in the pattern, fig. 3, which is then ready to mould. After the flask is filled with sand and packed as in ordinary moulding, the pattern, fig. 3, is withdrawn, and the roller *a* and pivot or wire *c* remain in the sand. A pair of small pincers made for the purpose is then extended into the print, from which the pattern, fig. 3, is withdrawn, and the sand that filled the slots or grooves *d d* is depressed towards the roller *a*, leaving the print smooth and ready to cast or pour. As the iron is poured into the mould, it forms around the ends of the wire or pivot *c*, and holds them firmly in their place. The frame *b* might be moulded in other ways and cast around the pivot or wire *c*, and when finished be substantially the same.

The ordinary mode of making trunk-rollers is to cast the frame *b*, and then drill a hole on each side and rivet in the pivot or wire *c*. The frames being very thin, it is necessary to have them thoroughly annealed before drilling. It often happens that the holes in the frames are not drilled opposite each other, and consequently the pivot and roller stand obliquely with the frame. The cheap help usually employed to rivet the frames break a large percentage of them. A great tension remains on many of those that are not broken, which causes them to break when fastened upon the trunk. By my invention I produce an article for trunk-rollers whereby all the above objections are entirely overcome. It is made with much less labor than the ordinary roller, and (not being drilled) of iron of a much cheaper and tougher grade. The iron being tougher and not afterwards annealed, the frames are much less liable to break.

I do not claim casting other articles of iron around a wire, neither do I claim any peculiar form or operation of the described roller; but what I claim as new, and desire to secure by Letters Patent, is—

As a new article of manufacture, a trunk-roller, with the frame *b* cast around the ends of the pivot or wire *c*, substantially as described.

HARVY GRAY.
